ATTORNEY.

UNITED STATES PATENT OFFICE.

DAVID DINBERG, OF OGDENSBURG, NEW YORK.

DESIGN FOR A CANDELABRUM.

60,448.

Specification for Design.

Patented Feb. 21, 1922.

Application filed November 4, 1920. Serial No. 421,771. Term of patent 7 years.

To all whom it may concern:

Be it known that I, DAVID DINBERG, a citizen of the United States, residing at Ogdensburg, in the county of St. Lawrence and State of New York, have invented a new, original, and ornamental Design for Candelabra, of which the following is a specification, reference being had to the accompanying drawing, forming part thereof.

The figure is a front elevational view of candelabra, showing my new design.

I claim:

The ornamental design for candelabra as shown.

DAVID DINBERG.
